UNITED STATES PATENT OFFICE.

WALTER S. WEBER, OF READING, PENNSYLVANIA, ASSIGNOR TO WILLIAM H. LUDEN, OF READING, PENNSYLVANIA.

BOX-LINING MECHANISM.

1,383,682.

Specification of Letters Patent. Patented July 5, 1921.

Application filed April 15, 1920. Serial No. 374,023.

To all whom it may concern:

Be it known that I, WALTER S. WEBER, a citizen of the United States, residing at Reading, in the county of Berks and State 5 of Pennsylvania, have invented certain new and useful Improvements in Box-Lining Mechanism, of which the following is a specification.

My invention consists in improved mechanism adapted particularly for automatically lining cartons having flaps for subsequently closing the same, and comprising means for cutting off strips from a roll of lining paper, forming the same into a folded 10 lining, and inserting the latter through an open end of each of a passing series of previously formed cartons or containers. Main objects are to provide for insuring the positive location of the cut-off lining 15 strips, and the proper alinement of the open flap end of a carton with the folding and inserting plunger notwithstanding natural variations in the cartons; for holding the flaps of the boxes advantageously below the 20 plunger; for automatically feeding the cartons to the reciprocating plunger; and generally for preventing waste of material and enabling a rapid and accurate operation essential to the securing of economical and 25 satisfactory results. The invention is fully described in connection with the accompanying drawings and the novel features are pointed out in the claims.

Figure 1 is a front elevation of a box 30 lining machine embodying my invention.

Fig. 2 is a cross-sectional elevation of the same on the line 2—2 of Fig. 1.

Fig. 3 is a sectional plan view on the line 3—3 of Figs. 1 and 2.

Fig. 4 is a sectional plan view on the line 4—4 of Figs. 1 and 2.

Fig. 5 is an enlarged detail front view of the folding devices, indicating a carton in position beneath the same, with the flap holding devices in position.

Fig. 6 is a similar longitudinal section at right angles to Fig. 5.

Figs. 7, 8, 9, and 10, are perspective views indicating the various steps in the folding 50 of the liner.

As shown in the drawings 2—2 represent the side frames of a machine, which suitably support a drive shaft 3, a lever pivot shaft 4, a feed roll shaft 5, a table 6, and a box car-

ton or container feed way shelf 7. The 55 drive shaft 3, which is rotated in any convenient manner, carries a series of cams operating upon a corresponding series of levers pivotally supported on shaft 4, which levers are adapted to actuate the various 60 coöperating mechanisms, hereinafter fully described, in due sequence and time to perform the necessary accurate forming of each box lining and insertion of the same into each passing box or container; the liner 65 paper 8 being continuously supplied from a roll 8^a carried on shaft 9, suitably supported in brackets of the side frames 2—2.

This liner paper 8, of proper width and preferably waxed to form a moisture proof 70 lining, is fed from the roll 8^a as shown, over idler rolls 10 and 11 to the feed roll 12 on shaft 5, and beneath roll 13 to the feed table 6. The rolls 10 and 13 are in frictional contact with the roll 12 so as to 75 rotate with the latter and insure the positive feeding forward of a certain amount of paper governed by each intermittent rotation of the roll 12. This intermittent movement of the roll 12 is effected, as shown, 80 by a cam 15 on the shaft 3, acting upon one arm 16 of a quadrant lever 17 pivotally supported on the shaft 4, its other arm 18 pivotally carrying a toothed rack bar 19 held in constant mesh with a gear 20; which gear 85 has a ratchet engagement with the roll 12 so that said roll will be positively driven in one direction only, the gear 20 rotating idly in the reverse movement of the rack in well known manner. This intermittent 90 feed of the roll 12 carries a determined length of paper to the feed table 6, pushing the same forward over one blade 21 of a shears, to a proper location to be acted upon by a plunger device hereinafter more fully 95 described. A movable shearing blade 22 is actuated as shown at proper times by cams 23, 24 on shaft 3, operating through bell cranks 25, 26 connected to said shearing 100 blade 22 by links 27, 28, so that the downward movement of said blade 22 will cut off from the roll of paper a lining blank of proper length. Spring fingers 29 are employed as shown to hold the blank during 105 the cutting operation; and I employ an air jet, as shown, from a supply nozzle 30, directing the same upon the end of the paper lying on the blade 21 to prevent any lifting

action thereon during the raising of the blade 22 after the cutting operation, thus insuring the proper feeding forward of the paper at the next rotation of the feed roll 12. The cut off blank 8^b is thus laid on the table 6 in proper position beneath a vertically reciprocated plunger; stop pins, if desired, being employed on the plate to guide the paper to its position.

10 This plunger 35 is of rectangular shape as shown, and is guided at its lower end in a bracket 36, and at its upper portion by the shaft 3; a slot 37 in said plunger embracing said shaft and permitting vertical movement thereon. Vertical reciprocation of this plunger 35 is controlled, as shown, by a cam 38 on the shaft 3, which cam effects a determined lifting action and is so shaped as to permit the plunger to fall by gravity for a purpose hereinafter further explained.

15 The cam 38 as shown, bears upon a roller 39 at the upper end of a slotted bar 40 strung upon the shaft 3 and having its lower end pivotally connected to one member 41 of a bent lever pivotally carried by the shaft 4; the other member 42 of which lever is pivotally connected to a link 43; and the upper end of this link is pivoted at 44 to the upper end of the plunger 35. A balance weight 20 45 may be attached if desired, to the bent lever 41—42, to regulate the momentum of the plunger. The lower end of the plunger 35 is slotted as shown, so as to form separated or spaced legs 35^a, and I preferably provide 25 heating coils 46 within said legs and connect them in any suitable manner, not shown, with an electric circuit, for heating the prongs to a desired temperature, as later 30 hereinafter explained.

35 The table 6 is provided with a rectangular opening 50 in direct alinement with the plunger 35, which latter passes therethrough in its descending movement to carry the placed lining blank 8^b with it, and upon 40 which the blank is shaped to form a lining preliminary to its insertion in the carton or container. Folding fingers 51—51, 52—52, and 53—53 are fixedly located in the path of the plunger directly beneath the table, as 45 shown, to coöperate with the rectangular opening and the descending plunger to properly fold the lining blank. These folding operations are shown diagrammatically in Figs. 7 to 10, and Figs. 5 and 6 clearly indicate the folding fingers. The plunger descending on the blank 8^b laid on the table over the opening 50 turns up the two sides *a*, *a*; the fingers 51—51, located as shown 50 mainly within the opening 50 turn in the bottom edges *b*, *b*; the fingers 52—52 then turn over on the plunger edge the extending portions *c*, *c*, of one of the sides *a*; and the fingers 53, 53 finally turn in on the folds *c*, *c* the extending edges *d*, *d*, of the other 55 side *a*. The lining blank 8^b is thus folded 60

65

into an open-end box shape upon the plunger, ready to be carried by the latter in its further downward movement to a properly placed carton or container as later hereinafter more fully described. I preferably add 70 pressing fingers 54, 54 as shown, below the folding 53, 53 to firmly press the folded side edges of the formed blank upon the plunger edges to firmly crease the same and retain the folds. And I have found in practice that 75 my specially shaped plunger end with its spaced legs 35^a 35^a works as satisfactorily as a solid rectangular plunger so far as the folding operation is concerned, with particular advantages as later hereinafter explained.

The box cartons or containers 60 shown, are previously formed and set up with their open flap ends uppermost and are fed along the feed way shelf 7 in a step-by-step movement to bring each box into approximate alinement with the plunger for insertion of a liner. This feed way shelf 7 has spaced side walls 61, 61 (Fig. 4) arranged to retain the boxes in vertical position, and a 90 file of boxes are inserted at one end and progressively moved along by a feed slide 62 having a flanged head 63 engaging the last inserted box. This slide is actuated at proper times by a cam 64 on shaft 3 acting 95 upon one end 65 of a lever 66 pivotally carried midway of its length by a shaft 4, and its opposite end 67 having a sliding pivotal engagement with a pin 68 on the feed device 62. The boxes are preferably moved along 100 the shelf 7 until the end one contacts with the light spring stop 69 at a position just slightly too far to be in absolute alinement with the plunger 35. Spring fingers 70 (Fig. 5) engage the box flaps to press them slightly 105 outward, and the descending plunger with a liner folded thereon as previously described, first contacts with the slightly inclined end flap to move the box rearward sufficiently to accurately aline the open box 110 with the plunger and permit the falling plunger to carry a liner into the box. This excess feed movement and slight return of the box on the shelf 7, insures its accurate placement notwithstanding unavoidable variations in the boxes, which inaccuracies would otherwise be multipleid by the number of boxes between the plunger 35 and the slide head 63. This slide head may be made adjustable, as shown, for accurately setting the 115 head to the average feed required, and the above described slight excess feed then cares for the little variations in the box sizes.

For automatically feeding the boxes one at a time to the slide shelf 7 for action of 125 the feed slide 62, I form, as shown, a feed way at right angles to the feed end of the shelf 7, the slide walls 80, 80, of which are spaced to guide the box edges, and the bottom being formed by an endless belt 81 suit- 130

ably operated to carry the boxes toward the shelf 7; the boxes sliding on said belt when shelf 7 is full. An air blast from pipe 82 is provided to retain the boxes in vertical position, and for light boxes this blast can be made sufficient to feed the boxes forward without the aid of the belt. The boxes are placed by the operator between the walls 80, 80, with the side flaps to the rear as shown, and they may be inserted in batches conveniently if desired, the feed slide 62 drawing them one at a time from this supply. It will be noted that the head 63 of the slide 62 has extensions 63^a which retain the boxes in the supply feed way during the forward movement of the slide, the return movement uncovering the space made vacant by the pushing forward of the boxes on the shelf 7, the belt or air blast then carrying the supply of boxes forward until the forward one occupies this vacant space ready for the next forward movement of the slide 62.

The operation will be readily understood from the foregoing detailed description of the various movements, the boxes being carried one at a time to a position under the liner forming and inserting plunger 35, which latter in its downward movement carries each severed lining blank through the table opening 50 and the alined folding fingers beneath the same, to form on the plunger a folded lining, so that further downward movement of the plunger carries this liner into the box. Difficulty has been experienced in retaining this lining in the box upon the return upward movement of the plunger, especially when waxed paper is employed as is generally desired. For this reason I have slotted the end of the plunger 35, and heated each of its prongs 35^a 35^a, as previously stated. This slotted end not only prevents the creation of a vacuum in the box by the withdrawal movement of the plunger, and consequent likelihood of the liner remaining on the plunger, but also permits of the limited heating required. This heating causes the paper lining to slide easily on the plunger, and also fixes the folded edges of the blank to their creased shape; but the heat slightly affects the glaze of the paper and this effect is reduced by the fork-shaped form of the plunger. In providing for lifting the plunger positively while utilizing gravity only to effect the forming and inserting of the blank, the weight of the plunger and the extent of the lift are so arranged as to secure a momentum sufficient for these purposes under normal conditions, but insufficient to crush an improperly formed or opened box presented to the plunger; such a box being readily removed and reused when the plunger is reraised, without stoppage of the machine. The preferred construction specifically presented may be readily modi-

fied without departing from the spirit of the invention.

What I claim is:

1. In a machine for lining sheet-material boxes; an apertured lining-blank support, a box support below the same, and mechanism for forming and inserting the lining comprising a gravity-operated plunger and means for adapting the momentum thereof to merely overcoming the normal resistance of forming and unobstructedly inserting the blank into the box.

2. In a machine for lining sheet-material boxes having up-standing closing flaps, comprising a reciprocative plunger, and a lining-blank support having a plunger aperture and forming devices for said blank; means for first feeding boxes successively to supported position below said plunger but slightly out of alinement therewith, and for subsequently positioning the same accurately by action of the descending plunger.

3. In a machine for lining sheet-material boxes having up-standing closing flaps, comprising a reciprocative plunger, and a lining-blank support having a plunger aperture and forming devices for said blank; means for feeding boxes successively to supported position below said plunger aperture but slightly out of alinement therewith; and flap-engaging means adapted to bend an up-standing box flap to an outward incline in the path of the descending plunger whereby contact of the latter is adapted to accurately position the box.

4. In a machine for lining sheet-material boxes having up-standing closing flaps, comprising a reciprocative plunger, and a lining-blank support having a plunger aperture and forming devices for said blank; means for feeding boxes successively to supported position below said plunger aperture comprising a force-jet nozzle positioned to continuously operate upon a series of movably supported boxes.

5. In a box lining machine comprising a lining-blank support having a plunger aperture and blank-forming devices, and a box support; a reciprocatively operated plunger formed with spaced-apart box-entering members.

6. In a box lining machine comprising a lining-blank support having a plunger aperture and blank-forming devices, and a box support; a reciprocatively operated plunger formed with spaced-apart box-entering members each provided with internal heating means.

7. In a box lining machine comprising a lining-blank support having a plunger aperture and blank-forming devices, and a reciprocatively operated plunger; a main box feed-way below said plunger adapted to contain a series of contacting boxes and having a supply extension arranged at right angles

thereto, and a reciprocating feed device in said main feed-way having a head portion adapted to serve as a closure for said right angled extension.

5 8. In a box lining machine comprising a lining-blank support having a plunger aperture and blank-forming devices, and a reciprocatively operated plunger; a main box feed-way below said plunger having a supply 10 extension arranged at right angles thereto, continuous but non-positive box feeding means in said supply extension, and a reciprocating feed device in said main feed-way having a head portion adapted to serve 15 as a closure for said right angled extension.

9. In a box lining machine, a main feed-way, an extension feed-way at right angles thereto, a headed reciprocating feed device for said main feed-way adapted to close and 20 open the exit end of said extension feed-way, and an air jet nozzle directed longitudinally of said extension feed-way to maintain the boxes therein in vertical position and exert feeding pressure thereon.

25 10. In a box lining machine, a main feed-way, an extension feed-way adapted to contain a series of contacting boxes at right angles thereto, a headed reciprocating feed device for said main feed-way adapted to 30 close and open the exit end of said extension feed-way, and a conveyer belt in said supply feed-way adapted to feed a box to

said container feed-way at each reciprocal movement of the feed-slide.

11. In a box lining machine, a main feed-way, an extension feed-way at right angles thereto, a headed reciprocating feed device for said main feed-way adapted to close and open the exit end of said extension feed-way, a conveyer belt in said supply feed-way 40 adapted to feed a container box to said container feed-way at each reciprocal movement of the feed-slide, and an air jet nozzle co-operating with said feed belt.

12. In a box lining machine, a vertically 45 reciprocated plunger, an apertured lining-blank support, an intermittently operated roll adapted to feed a lining strip to position under the plunger, and a knife for severing a measured lining blank, said knife having 50 holding fingers for retaining the severed blank in proper position beneath the plunger.

13. In a box lining machine, a vertically reciprocated plunger, an apertured lining-blank support, an intermittently operated 55 roll adapted to feed a lining strip to position under the plunger, a vertically reciprocated knife for severing a measured lining blank, and a force jet nozzle arranged to control the forward end of the outwardly fed 60 strip.

In testimony whereof I affix my signature.

WALTER S. WEBER.
